H. E. Curtiss

By *Clarance A. O'Brien*

Attorney

UNITED STATES PATENT OFFICE.

HAROLD E. CURTISS, OF MONROE, MICHIGAN.

CENTRIFUGAL SWITCH.

Application filed August 25, 1924. Serial No. 734,045.

To all whom it may concern:

Be it known that I, HAROLD E. CURTISS, a citizen of the United States, residing at Monroe, in the county of Monroe and State 5 of Michigan, have invented certain new and useful Improvements in Centrifugal Switches, of which the following is a specification.

This invention relates to an improved 10 automobile signal, and it has particular reference to a speed indicating signal, which I have devised to assist automobile drivers to determine the approximate speed of travel of a leading vehicle.

15 A device of this class is also useful to enable traffic officers to determine whether or not a machine is travelling at a speed not permitted by law.

The invention has more specific reference 20 to a device, which is to be utilized in conjunction with a constantly driven part of the automobile, and in carrying out the invention, I propose to install the novel circuit closing device, in the speedometer line at 25 an appropriate point between the operating wheel therefor and the meter on the instrument board.

The improved circuit closing device is preferably in the form of a speed controlled 30 governor which is active on a circuit closing element, cooperating with one of several electric circuit contacts, according to the speed at which the vehicle is driven.

For its novelty, the invention relates more 35 particularly to the specific construction of the governor and the casing in which it is confined.

There are other features of the invention, 40 and these will become apparent as the description goes on.

In the accompanying drawing, forming a part of this application, and in which like numerals are employed to designate like parts throughout the same;

Figure 1 represents a view, partly in section and partly in elevation, of the speed controlled circuit closing device.

Figure 2 shows an elevational view of a lamp box or signal used in conjunction with said device.

Figure 3 is a diagrammatic view of the wiring.

Directing attention first to the speed controlled circuit closing device, appearing in Figure 1, it will be seen that the same com-

prises a suitably shaped casing including an open ended cylinder 1 closed at its opposite ends by plates 2 and 3 respectively. The plate 2 is provided with an externally disposed screw threaded socket 4, at the bottom 60 of which is a centrally disposed opening. The plate 3 is formed with a similar socket 5. Extending through the opening in the socket is a rotary driven shaft 6. This shaft is provided on its upper end with the head 65 7, located in the socket 4 and provided with a groove forming a key way.

The opposite end of the shaft is formed with a head 8 located in the socket 5 and provided with a key 9. The key way in the 70 head 7 is adapted to receive the key 10, carried by the flexible driven shaft 11. The shaft 11 may be that of the automobile speedometer. As is usual, it is provided

75 with the flexible casing 12, and in the present instance, the casing is equipped with a coupling 13 to thread onto the socket 4. As above intimated, the governor is keyed or otherwise fixedly connected to the shaft 6 and is disposed within the casing. The governor 80 comprises a head 14 carrying the L-shaped weighted arms 15. As is customary, the weighted ends of the arms are connected together by one or more coil springs, to resist the outward swinging movement. In 85

the present instance, the inner reduced extremities of the laterally extended ends of the governor arms are received in a peripheral groove formed in the head 16 of a sliding sleeve 17, mounted on the shaft. At its 90 top, the sleeve 17 is provided with a flange 18, and interposed between this flange and the closing plate 2 is a coiled spring 19. The plate 2 is provided with an internal depending cylindrical guide 20, and the spring 19 is 95 confined therein, while the flange 18 is likewise confined and slidable. There are three electrical contacts 21, fitted in insulation blocks carried by the guide 20. Obviously,

the flange 18 is adapted to successively engage these contacts for closing the electric circuit seen in Figure 3. In this same figure, the reference character 22 represents the coupling carried by the casing of the speedometer shaft on the lower end of the device, this coupling being connected to the socket 5. At this end, the flexible shaft is provided with a head 23 having a key way for reception of the key 9 on the head 8. If desired, the casing may be provided with a remov- 100 105 110

able plug 24, to permit insertion of a lubricant.

As before stated, Figure 2 represents a suitably constructed lamp box 25. To accord with my invention, this box will be equipped with separate windows containing the inscriptions "Fast", "Slow" and "Stop". In Figure 3 I have shown the contacts 21 included in the electric circuit leading to the lights 26, 27, and 28, adapted to be contained within the compartment of the lamp box 25. 29 represents a suitable switch. 30 indicates a battery which is in electrical connection with the sliding sleeve 17 already referred to. In connection with this figure I might point out that the light 26 may be in the upper compartment of the box 25, the light 27 in the middle compartment, and the light 28 in the lower compartment. Obviously, as the shaft 6 is rotated by the flexible shaft of the speedometer, the governor will serve to raise or lower the sleeve 17 according to the speed of rotation of the shaft. Steady movement of the sleeve 17 is insured, by the action of the spring 19. When the flange 18 on the sleeve is in engagement with the lower contact, the word "Stop" will be shown. As the speed increases, the sleeve will be lifted, and the flange will come into contact with the middle contact, thus show-

ing the word "Slow". When the speed is abnormal, the circuit containing the remaining contacts will be closed to show the word "Fast".

I claim:

A device of the class described comprising a casing embodying an open ended cylinder, closing plates for the opposite ends of said cylinder, one of said plates being provided with internal and external sockets, the other plate being formed with an external socket, a rotary shaft extending through the casing and having heads on its opposite ends located in said external sockets, a plurality of relatively stationary contacts mounted upon the wall of the internal socket, a sleeve slidably mounted upon said shaft, said sleeve having a flange at one end co-operable with said contacts and having a grooved collar at its opposite end, a coil spring located in said internal socket and surrounding the shaft and bearing at one end against said flange, and a speed controlled centrifugal governor fixedly mounted upon said shaft within said casing, said governor having spring pressed L-shaped arms, the short inturned ends of which extend into the groove in said collar.

In testimony whereof I affix my signature.
HAROLD E. CURTISS.
